WORK HOLDING MEANS FOR SEWING MACHINES

Filed May 29, 1935

UNITED STATES PATENT OFFICE

2,095,615

WORK HOLDING MEANS FOR SEWING MACHINES

Jesse V. Poole, Abington, Mass., assignor to Puritan Manufacturing Company, Boston, Mass., a corporation of Massachusetts

Application May 29, 1935, Serial No. 23,964

14 Claims. (Cl. 112—62)

The specific primary object of the invention herein disclosed is to effect sewing of a seam in an innersole, for securing a stitching rib, or the reinforcement of such a rib, to the body of the innersole, with the stitches extending between the inner angle of the rib and the edge of such body. Innersoles of the character referred to are those used for the making of welt shoes, having a rib for reception of the inseam 5 stitches of the lasted shoe, and of which either the entire rib, or an inner reinforcing strip or sheet with upturned edges is attached to the innersole body. Such an innersole is shown in my application for patent Serial No. 3,897 filed January 29, 1935. The purpose of disposing the securing seam in the manner above briefly described is to avoid the presence of stitches on the surface of the insole which lies uppermost inside of the finished shoe; hence avoiding the necessity 10 of placing a sock lining in the shoe to cover such stitches, while providing the strength of connection between the innersole body and its rib which is afforded by a sewed seam, beyond the strength given by adhesive alone.

In the production of articles thus stitched, on a commercial scale at low cost by automatic sewing machinery, a serious and baffling problem was to insure correct and accurate placement of the stitches at the edge of the sole at the 15 proper distance from each of the faces of the sole; insuring that all stitches will pass through enough of the body substance to be properly formed and held from breaking out, while insuring on the other hand that they will not pass through to the inner surface, (the surface which comes next to the foot in the finished shoe). The present invention embodies my solution of this problem.

I have applied this embodiment to a sewing 20 machine of well known type, which sews a chain seam and feeds the work step by step by the coaction of an awl, a straight needle, a looper, and a cast-off. The commercial design of such a machine is shown in the accompanying drawing, but modified or altered by the addition of means 25 novel with the present invention for suitably locating the work piece in position to receive stitches in the manner described, and alternately releasing and gripping it to permit feeding 30 and rigidly holding the work, respectively.

Notwithstanding what has been said above about the specific purpose, problem and embodiment of the invention herein disclosed, it is to be understood that the protection which I seek 35 extends to all means and combinations equiva-

lent to those hereinafter described and set forth in the claims, for all useful purposes to which they may be adapted, and in combination with stitch forming mechanisms of any character with which they may be operatively combined. That is, for instance, the invention is not limited to combination with chain stitch sewing means or instruments for sewing either a chain stitch or a lock stitch seam with the aid of straight, rather than curved, needle and awl.

Describing now the specific embodiment of the invention herein illustrated,—

Fig. 1 of the drawing shows in side elevation a standard type of chain stitch sewing machine equipped with work supporting, guiding and gripping means embodying this invention;

Fig. 2 is a side elevation on a larger scale, partly broken away and shown in section, of the elements in which this specific form of the invention has been embodied as attachments to a standard commercial machine;

Fig. 3 is a front elevation of the parts shown in Fig. 2;

Fig. 4 is a perspective view of the work supporting member of the attachments above referred to;

Fig. 5 is a perspective view of a fragment of an inner-sole (shown on an enlarged scale), stitched by the use of the means shown in the preceding figures.

Like reference characters designate the same parts wherever they occur in all the figures.

As illustrating the problem which I have solved by this invention, attention is directed first to the innersole shown in Fig. 5. *a* is the body of such innersole, which may be of leather, leather-board, or any other natural, artificial or fabricated substance suitable for such articles. *b* represents a rib for reception of the stitches of the inseam of the lasted shoe; which may be made of an originally separate strip of any suitable material bonded to the body by cement or a coalesced impregnant; or may be an integral flap formed by channeling into the contiguous surface of the body and bent upward. *c* represents reinforcement for the rib; here shown as a strip of textile fabric bent on an intermediate longitudinal line to fit into the inner angle between the body and rib. It typifies any such reinforcement, of whatever material made, and whether made from a relatively narrow strip, or from a sheet of fabric wide enough and properly shaped to cover the entire area of the sole within the rib and bent up at its edges against the inner surface of the rib. *d*, *d* represent the stitches

of a seam passing through the reinforcement at the angle thereof and through the contiguous substance of the body to the outer edge thereof in a location between the broad faces of the body. 5
 5 This seam is an important factor of the inner-
 sole, as it perfects a connection between the rib
 reinforcement and the innersole body additional
 to that of the cement or adhesive with which the
 reinforcement is secured before stitching, and
 10 of more permanent character. The location of
 the outer loops of the stitches in the edge of
 (that is, the face which comes next to the foot
 of the wearer in the finished shoe) entirely free
 15 of stitches, hence with its original smoothness
 unimpaired, and avoids the need of a sock lining
 to cover the roughness which would otherwise
 be caused by stitches passing through to such
 inner surface. However, the placement of stitches
 20 in the manner shown, particularly in a thin inner-
 sole, so that they will neither break out nor
 mar the inner surface, was a difficult problem.
 It was necessary to insure placement of the
 25 outer loops of the stitches far enough from the
 face which carries the rib to anchor them
 against tearing or cutting the sole substance and
 pulling out, while at the same time avoiding danger
 of passing through to the inner face of the
 30 sole at too great a distance from the edge. It
 was highly desirable also, if not actually essential,
 to insure placement of the stitches in an
 even line.

In Figs. 1 and 2 of the drawing, the numerals
 11, 12, 13 and 14 represent respectively the awl,
 35 needle, cast-off, and looper of a commercial chain
 stitch sewing machine. The awl is carried by a
 reciprocative awl bar 15 and the needle and cast-
 off by parallel reciprocative bars, only one of
 40 which appears in the drawing, and is designated
 16. These bars are reciprocated in proper time
 with one another, and the looper is moved in a
 curved path, by the means for that purpose with
 which the commercial machines are equipped.
 Being well known, such mechanisms require no
 45 description here and are merely suggested by
 dotted lines in Fig. 1. The needle and cast-off
 bars are mounted in an oscillative carrier 17
 which moves in a plane perpendicular to the
 plane of Fig. 1 for feeding the work.

50 On a pedestal 18, rising from the base of the
 machine, is mounted a work support 19. This
 support has guide portions 20 fitted adjustably
 in guideways in the pedestal, whereby it may be
 moved forward or back for adjustment; and it
 55 is secured by suitable clamping means, shown
 here as set screws 21. The work engaging por-
 tion of this support is a forwardly extending
 nose 22 having a slot 23 through which the needle
 passes and in which it may move for feeding.
 60 The front and rear faces of the nose are in-
 clined to the path of the needle and awl at
 angles suitable to enter the inner rib angle of
 the sole, as shown in Fig. 2, when the sole is
 held with the line in which the stitching thread
 65 is to be passed in alinement with the awl and
 the needle.

A presser foot 24 and a gripper 25 cooperate
 with this work support. The presser foot is car-
 ried by the lower extremity of a vertically recip-
 70 roating presser bar 26. It bears downwardly
 against the innersole rib and presses the latter
 against the rear inclined face of the work sup-
 port nose. The gripper is forced laterally to the
 rear and presses the margin of the sole against
 75 the adjacent side face of the presser foot, while

at the same time pressing the sole against the
 outer face of the nose, at least to the extent
 that it overlaps such outer face. An abutment
 5 27 is supported on the body portion of the work
 support beside the rear face of the presser foot
 to prevent deflection of the latter by the lateral
 thrust of the gripper. This abutment is adjust-
 able in the front to rear direction, and is clamped
 by screw heads 28 of which the shanks pass
 through enlarged holes in the base member of
 the abutment and are screwed into the body
 part of the work support. 10

The gripper is carried by an arm 29 pivoted
 at 30 to a bracket 31 on the side of the over-
 hanging head 32 in which the awl bar and presser
 bar are confined with capacity for reciprocating
 movements. A spring 33 presses the gripper
 carrying arm 29 inward or rearward. This spring
 surrounds a rod 34 which passes freely through
 a hole in the arm 29 and is made fast at its
 rear or inner extremity to a projecting rigid part
 35 of the bracket 31. An adjustable nut 36 on
 the outer end of rod 34 serves both as an abut-
 ment for the spring and as a means to adjust
 the force exerted by the spring on the gripper.
 20 An adjustable stop screw 37 carried by the arm
 is arranged to abut against the bracket projec-
 tion 35 to establish the limit of inward or rear-
 ward movement of the gripper. By the proper
 30 adjustment of the agencies last described, the
 sole edge may be firmly gripped and correctly
 located to receive the stitches *d* of Fig. 5.

To permit feeding of the work, the grip of the
 holding members must be relaxed after each
 stitch has been formed. Release is effected in
 35 part by the rise of the presser foot and in part
 by withdrawal of the gripper. Rise and descent
 of the presser bar in proper sequence with the
 movements of the stitch forming mechanism are
 effected by mechanisms of the standard machine.
 40 The gripper is moved by the presser bar through
 the agency of a roll 38 and a cam 39. The roll
 is mounted on a bracket 40 secured to the presser
 bar, while the cam is secured to the gripper car-
 rying arm. The cam is a wedge-like block hav-
 45 ing an inclined face 41 on which the roll bears.
 It is secured to the arm by screws 42 passing
 through elongated slots 43, which permit ad-
 justment longitudinally of the arm; and the
 bracket 40 is similarly adjustable along the
 50 presser bar, and is made fast by a set screw 44.
 These adjustments permit accurate timing and
 placement of the gripper.

The mode of operation will be so plain from
 the foregoing as to need no further description.
 55 It may be noted that, while the presser bar neces-
 sarily moves slightly as the gripper comes into
 firmly gripping engagement, and as it commences
 to withdraw, such movement of the presser foot
 is resisted only by sliding friction with the work-
 60 piece and has no effect detrimentally or other-
 wise on the work.

In case it is desired to locate the stitches at
 a different angle to the plane of the sole than
 that shown, other supporting and gripping means
 65 of different surface configuration may be sub-
 stituted for those here shown, or some of them.
 For instance, the sole may be held at a different
 inclination from that shown in Fig. 2, or its
 margin may be bent or curved more or less
 70 sharply; results which may be obtained by ad-
 justing these members or by substitution of
 equivalent members for one or more of them,
 or by both substitution and adjustment. The
 gripper 25 is shown as detachably secured to its
 75

carrying arm 29 by screws 45 to facilitate substitutions. Similarly the presser foot 24 may be detachably secured to the presser bar, as will be understood by those skilled in the art without illustration of any specific detachable fastening. The manner in which the work support 19 is secured to the pedestal 18 permits its easy removal and substitution of specifically different equivalent supports.

10 While the presser bar in the machine here shown in essentially the same as those used with the commercial machines to which the present embodiment of the invention has been applied, the presser foot is different, for it not only operates by downward pressure with an underneath support, but it also cooperates by lateral pressure or reaction with a rearwardly pressing gripper. Its opposite faces, which engage the work and the abutment 27 respectively are parallel with its line of movement.

15 What I claim and desire to secure by Letters Patent is:

20 1. In a sewing machine having a reciprocative needle and complementary stitch forming means, work holding means adapted to hold an inner-sole of the type having a rib projecting from one face in a line back from its edge, for placement of stitches extending between the inner rib angle and the nearer edge of such innersole, comprising 25 a support having work engaging surfaces respectively at opposite sides of the needle path and oppositely inclined thereto, and gripping members arranged to press the rib of the innersole against one of such faces and the body part of 30 the sole against the other face, while grasping the edge part of the sole between them.

25 2. In a sewing machine having a needle movable back and forth in a prescribed path, a support having work-engaging surfaces at respectively opposite sides of such path and inclined thereto oppositely to one another, a presser arranged to cooperate with one of said faces in gripping the work, and a gripper arranged to cooperate with the other of said faces and with a 35 side of the presser in gripping the work, said presser being movable toward and away from the work support in a given path and the gripper being movable back and forth in a path transverse to that of the presser in line with the work 40 gripping position of the presser.

30 3. The combination in a sewing machine with a reciprocating presser bar, a reciprocating needle, and associated stitch-forming means, of a work support having inclined faces respectively at opposite sides of the needle path and oppositely inclined thereto, a presser foot carried by said presser bar in position to cooperate with one of such inclined faces to grip the work, a cooperating gripper arranged to coact with the other face of 35 the work support and with the nearer side of the presser foot in gripping the work, and means to actuate the presser bar and complementary gripper for grasping and releasing the work in a prescribed sequence with respect to the operations 40 of the needle and associated stitch-forming means.

35 4. The combination in a sewing machine with a reciprocating presser bar, a reciprocating needle, and associated stitch-forming means, of a work support having inclined faces at opposite sides of the needle path, a presser foot carried by said presser bar in position to cooperate with one of such inclined faces to grip the work, a cooperating gripper arranged to coact with the other face 45 of the work support and with the presser foot in

gripping the work, said gripper being movable in a path transverse to the path of movement of the presser foot, and an abutment at the opposite side of the presser foot from the cooperating gripper having a presser foot engaging face parallel to the line of movement of the presser foot.

5 5. In a sewing machine having a reciprocative presser bar, a reciprocative needle and cooperating stitch-forming means; a work support having a work engaging face at an inclination to the line of movement of the presser bar, a presser foot carried by said bar to cooperate with the said inclined face in gripping the work, and an abutment arranged to engage the presser foot at the opposite side thereof from the said work support 10 surface, the engaging face of said abutment being parallel to the line of movement of the presser foot.

15 6. In a sewing machine, a reciprocative presser bar, a presser foot carried thereby, a cooperating gripper movable toward and away from the presser foot in a line transverse to the movement of the latter, yielding means acting on said gripper tending to move it toward the presser foot, and complementary wedging members connected 20 with the presser bar and gripper respectively organized to cause recession of the gripper when the presser bar moves in one direction and to permit advance of the gripper when the presser bar moves in the opposite direction.

25 7. In a sewing machine, a reciprocative presser bar having a presser foot at one end, an arm pivoted to the machine structure beside the presser bar and having a gripper movable toward and away from one side of the presser foot, and co- 30 operating means carried by the presser bar and arm respectively, arranged to cause movement of the arm and gripper away from the presser foot when the presser bar moves in one direction and to cause approach of the arm and gripper 35 toward the presser foot when the presser bar moves in the opposite direction.

35 8. In a sewing machine, a reciprocative presser bar having a presser foot at one end, an arm pivoted to the machine structure beside the presser 40 bar and having a gripper movable toward and away from one side of the presser foot, cooperating means carried by the presser bar and arm respectively arranged to cause movement of the arm and gripper away from the presser foot 45 when the presser bar moves in one direction and to cause approach of the arm and gripper toward the presser foot when the presser bar moves in the opposite direction, and a presser foot abutment at the opposite side of the presser foot from 50 said gripper with which the presser foot is in sliding engagement.

55 9. In a sewing machine, a reciprocative presser bar having a presser foot at one end, an arm pivoted to the machine structure beside the 60 presser bar and having a gripper movable toward and away from one side of the presser foot, co- operating means carried by the presser bar and arm respectively arranged to cause movement of the arm and gripper away from the presser foot 65 when the presser bar moves in one direction and to cause approach of the arm and gripper toward the presser foot when the presser bar moves in the opposite direction, and a work support having opposite work engaging faces so inclined that 70 they converge toward one another and toward the space between the presser foot and gripper.

75 10. In a sewing machine, a reciprocative presser bar having a presser foot at one end, an arm pivoted to the machine structure beside the 75

presser bar and having a gripper movable toward and away from one side of the presser foot, co-operating means carried by the presser bar and arm respectively arranged to cause movement of the arm and gripper away from the presser foot when the presser bar moves in one direction and to cause approach of the arm and gripper toward the presser foot when the presser bar moves in the opposite direction, a work support having opposite work engaging faces so inclined that they converge toward one another and toward the space between the presser foot and gripper, and an abutment at the side of the presser foot opposite to the gripper having a face in sliding engagement with the presser foot and extending in the direction of reciprocation thereof.

11. In a sewing machine, the combination with stitch forming mechanism, of a work support having convergent faces adapted to be embraced by portions of a work piece, a presser foot movable toward and away from one of said faces to press one portion of the work piece against said face, and a presser arranged and operated to press another portion of the work piece against one side of the presser foot and against the other convergent face of the work support.

12. In a sewing machine, the combination with stitch forming mechanism including a needle movable in a prescribed path, of a work support, a presser foot movable toward said work support into work-gripping relation thereto at one side of the needle path, and away therefrom, and a gripper movable toward and away from the presser foot at the opposite side of the needle path in a line transverse to the movement of the presser foot, and in position to press the work against the side of the foot when the latter is in work-gripping position with respect to the work support.

13. A sewing machine for placing a seam in a

ribbed innersole between the inner angle of the stitch receiving rib of such innersole and the outer edge of such sole along a line in such edge intermediate the surfaces of the sole, comprising a work support having convergent faces adapted to be embraced by the body and rib of the innersole in the inner angle thereof, such work support having a needle passage between said convergent faces, complementary grippers organized to grasp the edge portion of the innersole between them and to press the body and rib parts of the innersole against said convergent faces, a needle reciprocatively mounted to travel in a path extending through the said passage of the work support and thence through the gripped part of the innersole and across its edge, work feeding and stitch forming means cooperating with said needle to feed the innersole and form stitches, and means operating said grippers to grip and release the work in proper timing with the operations of said needle and cooperative means for the sewing of a seam in the location specified.

14. In a sewing machine having a needle movable back and forth in a prescribed path, a work support mounted across, and having convergent work-engaging faces at respectively opposite sides of, such path, said support being adapted to occupy the inner angle between the body and stitching rib of a ribbed innersole of the type used in making welt shoes, a presser arranged and operating to grasp the rib of such an innersole between itself and one of such faces, and a gripper arranged and operating to grasp the marginal part of the innersole body between itself and the other of said faces and the presser; whereby to hold points in such inner angle and the adjacent edge of the innersole in the needle path.
